CLAIM

The ornamental design for a cap for bottle, as shown and described.

DESCRIPTION

FIG. 1 is a front elevational view of a cap for bottle showing my new design, with a bottle shown in phantom line as environment only and forming no part of the design;
FIG. 2 is a top plan view thereof;
FIG. 3 is a side elevational view thereof, the opposite side being the same; and,
FIG. 4 is a rear elevational view thereof.
